VARIABLE INDUCTORS

David T. Geiser, North Adams, Mass., assignor to Sprague Electric Company, North Adams, Mass., a corporation of Massachusetts

Application October 21, 1955, Serial No. 542,061

1 Claim. (Cl. 336—73)

This invention relates to toroidal inductors, and more particularly to toroidal inductors of the type whose inductance can be selectively varied.

Variable inductors are used in various types of radio and higher frequency applications. They may be used for intermediate-frequency transformers, medium wave-band coils, short wave coils, radio-frequency chokes, and various higher frequency applications such as in television service, etc.

Q , or the Q factor, can be defined as two pi times the ratio of energy stored to energy dissipated per half cycle of sine wave excitation. It is indicative, therefore, of the operating efficiency of the coil. For optimum operating characteristics, a maximum Q should be obtained in a minimum volume or space occupied by the coil. Another important factor is economy of construction.

An object of this invention is to provide novel structures for variable inductors which are economical to manufacture and provide efficient operating characteristics.

In accordance with this invention, a magnetic core of endless construction is wound with a flux inducing winding. A flux producing means is associated with said core for reacting with the flux induced by the winding to form a leakage field about the core.

An element of flux-controlling material is disposed adjacent the core. This element is movably mounted to permit it to be selectively inserted within the leakage field to provide means for varying the inductance of the winding.

The novel features of the present invention will become apparent to one skilled in the art from a reading of the following description, in conjunction with the accompanying drawings in which:

Fig. 1 is a somewhat diagrammatic representation of one embodiment of the present invention;

Fig. 2 is a somewhat diagrammatic representation of another embodiment of the present invention;

Fig. 3 is a somewhat diagrammatic representation of still another embodiment of the present invention;

Fig. 4 is a somewhat diagrammatic representation of a further embodiment of the present invention; and

Fig. 5 is a perspective view of a portion of another embodiment of the present invention.

Identical parts throughout the various figures are designated by the same reference characters, followed by suffixes in indicative sequence.

In Fig. 1 is shown a variable inductor 8. A doughnut or toroidal-shaped endless core 10 of magnetic material is provided. The core is made of any magnetic material having a minimum permeability of approximately 2. It may be, for example, of powdered iron bonded together by a resin and pressed. Although doughnut-shaped toroids are shown in the drawings, endless cores of any shape such as elliptical or angular may be utilized to advantage. For higher frequencies, ferrites of the type described in U.S. Letters Patents No. 2,579,978, No. 2,452,529 and No. 2,452,530 are particularly suit-

able. The core 20 may also be made of insulated spirally wound foil or wire. For lower frequencies, ring-shaped laminations may be bonded or clamped together to form a core.

5 A number of turns of conductive wire 12 are looped or wound around a portion of the core 10 to form a winding 13. The core, for example, may be a toroid having an outer diameter of 0.60 inch, an inner diameter of 0.27 inch, a cross-sectional area of 0.023 square inch, and an initial permeability of 8. When the core is made of a ferrite having a high electrical resistivity, the wire need not be specially insulated from the core. The winding provided by the conductive wire 12 may be formed of a number of equally spaced loops of conductive wire.

10 The wire may be bare or covered by insulation such as those of the type known as Formvar or Ceroc-T. Litz wire of the braided or unbraided type also may be used. Formvar is a vinyl acetal enamel and magnet wire coated with this insulation is obtainable from the Acme 15 Wire Co. of New Haven, Connecticut. For a description of the structure and properties of the Ceroc-T type wire, refer to U.S. Letters Patent No. 2,707,703. The winding may, for example, be made up of ten turns of No. 26 wire of the aforementioned types. The winding formed by wire 12 is connected across a source of alternating current 14 which may be R.F., U.H.F., etc.

20 A sheet-shorted turn 16 is disposed about another portion of the core 10. The sheet-shorted turn is made of a sleeve of conductive material. This material may 25 be, for example, conductive foil stock. The sleeve may be formed by looping a sheet of foil about the core and then soldering the outer edge. A sheet material printed or plated with a conductive pattern may also be used for the sheet-shorted turn. This sheet-shorted turn can be 30 insulated or uninsulated from the core whether the core is made of conductive material or non-conductive material.

35 A pair of protuberances or poles 18 and 20 can be provided on the inner portion of the core 10. These 40 protuberances 18 and 20 are oppositely disposed across the central aperture 22 of the core 10. These poles 18 and 20 are disposed on an axis lying approximately between the winding 13 and the sheet-shorted turn 16. They provide a path to help leakage flux transverse the 45 aperture 22.

40 A slug 24 is mounted within the aperture 22 by means permitting axial movement of the slug within the aperture. The slug 24 slides in a channel provided by protuberances 18 and 20. This slug is a flux-controlling 50 member and therefore is made of either highly permeable material or highly conductive non-magnetic material. Insertion of the slug within the aperture therefore varies the effective permeability of the core. This in turn results in a change in the inductance imposed on the source of 55 alternating potential 14 by the variable inductor shown in Fig. 1.

55 For a wide variation in inductance, the slug 24 may be divided into a highly permeable portion 26 and a non-magnetic highly conductive portion 28. The highly permeable section may be, for example, soft iron and the non-magnetic portion 28 may be brass or copper.

60 There may also be provided a cap or disc-like piece which bridges across a face of the core to effect a further variation in inductance by being adjustably positioned 65 with respect to the core. This cap can be of the same inductance-controlling materials indicated above for the slug 24, and may also be formed integral with the slug or used without the slug, if desired.

65 Portions 26 and 28 of slug 24 may be selectively positioned within the aperture 22 by sliding the slug 24 to and fro. Where a fine adjustment is desired, the slug and inner surfaces of the poles 18 and 20 may be coopera-

tively threaded to permit axial positioning of the slug by rotation thereof.

Variable inductors embodying the structure shown in Fig. 1 have yielded a wide range of inductance variation at relatively high Q factors.

In Fig. 2 is shown a variable inductor 8a similar to the inductor 8 shown in Fig. 1. The inductor 8a includes an endless or toroidal core 30, similar in composition to toroidal core 10 of Fig. 1. The core 30, however, includes a recessed slot 32 within which a close wound or lumped winding 34 is contained. The winding is made up of wire 12a of similar composition to that of wire 12 shown in Fig. 1. Protuberances 18a and 20a are provided on the toroidal core 30. These protuberances are similar in structure and function to protuberances 18 and 20 shown in Fig. 1. A sheet-shorted turn 36 is looped about another portion of the core 30. The sheet-shorted turn is made up of sheet material of a composition similar to that of the sheet-shorted turn 16 shown in Fig. 1. Sheet-shorted turn 36 is, therefore, made up of copper foil stock. For a half-inch nominal (average) diameter toroidal core 30, sheet-shorted turn 36 may be made of a strip of one mil copper tape $\frac{3}{8}$ " wide. The sides of the tape are slit to form four parallel strips. The central portion of the tape remains intact to form a shorting band throughout the length of the resultant loop. The intact portion of the tape is placed within the central portion of the core and the outer strips, which may be designated as 36₁, 36₂, 36₃, and 36₄, are radially bent about the core to form four loops joined by the intact central portion. The intact central portion of the turn is designated by reference character 38. The outer mating edges of the looped strips 36₁ to 36₄ are conductively joined at their outer edge. They are soldered, for example.

The structure 8a shown in Fig. 2 provides a convenient method of forming a sheet-shorted turn which provides the same favorable operating characteristics which are provided by the structure 8 shown in Fig. 1. The close wound winding 34 provides Q factors which are relatively higher than those provided by even spaced winding 13, shown in Fig. 1. In close winding the turns may be wound at random on top of each other. The recess 32 provides means for winding a core without making the structure bulky as well as leaving the protruding inner portions of the core to act as poles. The recessing of the sheet-shorted turn is also seen to have these advantages. Various inductance-varying structures may be, therefore, moved into close proximity with the core without being interfered with by the flux-inducing winding.

In Fig. 3 is shown a variable inductor structure 8b, including a sheet-shorted turn 40 which is painted upon the core 10b. The core 10b is made of a highly resistive ferrite of the type described in conjunction with Fig. 1. Protuberances of the type designated by reference characters 18 and 20 in Fig. 1 may be optionally provided.

This core 10b is, for example, made of a fired equimolar mixture of nickel oxide (NiO) and ferrous oxide (Fe₂O₃). These mixing weights are accurate within $\frac{1}{10}$ of 1%. This material is prepared in the normal manner to form the toroidal core. Other acceptable formulations for the core are described in previously mentioned Patents No. 2,579,978, No. 2,452,529 and No. 2,452,530.

The sheet-shorted turn is formed of highly conductive material. A silver turn provides extremely high conductivity. A silver turn is applied to the core 10b by painting approximately half of the core with silver paint which is baked to harden. A winding 13b is provided of wire 12b, which is similar in composition and function to that shown in Fig. 1.

In Fig. 4, a variable inductor structure 8c is shown. It is formed of a core 50 which is made of two halves, 52 and 54. The core half 52 is made of a ferrite of similar construction to the core of Fig. 1. The core half 54, however, is made of a magnetized permanent magnet material. The core half 54 may be made, for example, of

4
a permanent magnet material of the type known as Magnadur. Magnadur is a material which may be obtained from the Ferroxcube Corporation of Saugerties, New York. It is manufactured by mixing oxides having the approximate formula BaFe₁₂O₁₉. The oxides are pressed or extruded into a suitable shape and sintered. This forms a hard, rather brittle substance having excellent permanent-magnet qualities. This permanent-magnet core half may be also formed of other permanent magnet materials, such as Alnico. Alnico I may be used, for example. It is a permanent magnet alloy whose average composition is as follows: iron—62%, nickel—21%, aluminum—12% and cobalt—5%. A winding 13c formed of wire 12c is provided on the core half 52. An inductance varying slug 24c is provided in the inner portion or aperture of the core 50 to vary the inductance in a similar manner to that shown and described in conjunction with Fig. 1. Alternatively, the use of a permeable tuning slug 24c will cause a division of permanent magnet flux between the core 50 and the slug 24c, permitting utilization of somewhat lower frequency material in higher frequency applications while giving greater adjustable inductance range.

This structure provides a relatively high amount of leakage flux between the poles or protuberances 18c and 20c. Movement of slug 24c, therefore, varies the inductance over a wide range. This inductance variation is accomplished at relatively high Q factors over the entire range of variation.

In Fig. 5 is shown an inductance-varying means 24e which, for example, may be employed to vary the inductance of a toroidal core in a manner similar to that accomplished by portion 28 of slug 24 shown in Fig. 1. This inductance-varying means may be described as a cage. It is made up of two vanes 82 and 84, crossed at right angles. These vanes are made of non-magnetic highly conductive material. These vanes, for example, are made of sheet brass. These vanes are supported upon the enlarged head 86 of a rod 88. The rod 88 provides means for selectively inserting the cage within the aperture of the core.

The sheet-shorted form of the present invention should extend along at least about one-sixth of the endless path defined by the toroid. If less inner circumferential sheet length becomes desirable, it is possible to form separate sheet loops of highly conductive material bounding that portion of the toroid opposite the flux-inducing winding. Somewhat better Q's are generally obtained when the turns of the winding are closely wound, that is confined to only about one-fourth of the toroid path or less.

More than one winding can be used per core, as for example to make two-winding transformers suitable for use as intermediate frequency transformers in frequency-modulation receivers or AM-receiving sets, preferably those having intermediate frequencies of at least about 5 megacycles per second.

Although substantial variation can be made, one example of inductor according to the present invention has a toroid with a 0.28 inch internal diameter, a 0.48 inch external diameter, the ring having a uniform square cross-section, except at inner poles 0.06 inch wide protruding inward 0.01 inch radially; the shorted turn is made of 1 mil thick copper foil extending $\frac{3}{8}$ " inch around the toroid path at its inner diameter and cut into four equal loops all soldered together, with 10 turns of No. 26 heavy Formvar wire extending half way around the core. Such an inductor in which the core is nickel ferrite, shows at 47.25 megacycles per second an inductance of 0.866 microhenry, a Q of 169, when tuned with a capacitance of 13.25 micro-microfarads. With a slug having a permeability of 12, the inductance can be raised to 0.984 microhenry, with a Q of 139 and a tuning capacitance of 11.42 micro-microfarads. The further addition of a cap with a permeability of 6.8 increases the inductance to 1.033, lowers the tuning capacitance to

11.03 micro microfarads, and does not change the Q. In general, it is preferred to operate at frequencies at least as high as 10 megacycles per second, using wires having an effective thickness corresponding to from No. 14 to about No. 30.

As many apparently widely different embodiments of this invention may be made without departing from the spirit and scope hereof, it is to be understood the invention is not limited to the specific embodiments hereof except as defined in the appended claim.

I claim:

A variable inductor comprising a one-piece toroidal core of magnetic material having a central aperture, a winding looped about said core, means for applying an alternating current signal to said winding to induce magnetic flux in said core, a thin layer of silver paint baked about the surface of approximately half of the said core having extremely high conductivity for reacting with said flux induced in said core by said winding to cause a leakage field of flux to traverse said central aperture 20 a pair of protuberances oppositely disposed on the inner

portion of said core on an axis across the central aperture, said axis lying approximately between said winding and said layer of silver paint, a slug of flux-controlling material disposed adjacent said aperture, a first portion of said slug being composed of a highly permeable material, a second portion of said slug being composed of a highly conductive non-magnetic material and movable means mounting said slug adjacent said aperture in a manner permitting selective insertion of said slug within said aperture for widely varying the inductance of said winding.
